(57) **CLAIM**

The ornamental design for a column guard, as shown and described.

DESCRIPTION

FIG. 1 is a top, left and front perspective view of a column guard showing our new design;

FIG. 2 is a bottom, left and front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is the top, left and front perspective view of the column guard.

The broken lines shown in FIGS. 1-9 illustrate portions of the column guard that form no part of the claimed design. The additional broken lines shown in FIG. 9 illustrate environment and form no part of the claimed design.
